UNITED STATES PATENT OFFICE

EDWIN O. ROE, OF NEW BEDFORD, MASSACHUSETTS, ASSIGNOR TO NATIONAL SPUN SILK CO., INC., OF NEW BEDFORD, MASSACHUSETTS, A CORPORATION OF MASSACHUSETTS

TEXTILE MACHINE

Application filed June 1, 1927. Serial No. 195,615.

This invention relates generally to textile spinning machines and has particular reference to mechanisms for forming into a roving the slivers and the like coming from carding, combing and similar machines.

One object of the invention is to provide a mechanism which will serve satisfactorily to gather the material coming from carding, combing and similar machines into a roving which is substantially twistless, but in which the fibers have sufficient mutual adhesion to make possible subsequent handling, drawing and spinning operations without the fibers separating or pulling apart. This is effected by giving the material a false twist as it is being converted into a roving without retaining any appreciable part of the twist in the roving.

In the present embodiment the invention is shown applied to or embodied in a rotary trumpet such as has heretofore been used to gather a ribbon-like sliver into a roving. The rotary movement of the prior trumpets is largely effected to minimize and distribute wear upon the interior of the trumpet by the material drawn through a passage extending axially through the trumpet. Any twist given to the material by the rotary movement of the prior trumpets is more or less accidental and is always so slight as to have no function in the formation of the roving. In applying the present invention to the prior trumpets, the trumpet is so constructed that the material, in going through the trumpet, passes through or over a portion which is eccentric to the axis of the trumpet.

The material is drawn from the delivery devices through the trumpet and eccentric portion by a pair of rollers. As a result of the construction of the new trumpet, the material between the delivery devices and the rollers is given a twist in opposite directions at either side of the eccentric portion. However, the rollers are spaced far enough from the outlet end of the trumpet and are driven at such a speed with reference to the rotations of the trumpet that one twist is offset by the other before the twist can be retained by the rollers and the roving therefore enters the nip of the rollers in untwisted condition.

The false or temporary twist serves, however, to compact the roving and cause better mutual adhesion of the fibers, so that in subsequent operations the roving may be handled as safely as if it had a twist. The untwisted condition is, however, much better for following operations, such as drawing, particularly if the material is composed of long fine fibers.

With the foregoing and other objects in view, the invention consists in a novel construction and arrangement of parts, the novel features of which are pointed out in the appended claim, and a preferred embodiment of which is hereinafter described with reference to the drawings accompanying and forming a part of this specification.

In said drawings:

Fig. 1 is a top plan view of the improved trumpet and some of the parts supporting and associated with it.

Fig. 2 is a section on the line 2—2 of Fig. 1.

Fig. 3 is a section on the line 3—3 of Fig. 2.

In the construction illustrated in the drawings the rotary trumpet 10 is supported by a suitable frame, such as the frame 11, having an elongated slot 12 to accommodate a bolt or similar device whereby the frame may be adjustably secured to a carding or similar machine. The frame 11 is formed as at 13 and 14 to produce the lower halves of journals or bearings to accommodate the trumpet 10. The upper halves of the journals or bearings are carried by plates or caps 15 and 16 secured by screws 17 to extensions 18 on the lower halves of the bearing.

The plates or caps 15 and 16 are provided with oil holes 19 and clamped between the plates 15 and 16 and the extensions 18 are pieces 20 of flannel, or other suitable material, extending over the trumpet 10 and under the oil holes 19. This construction provides a way of oiling the bearing for the trumpet which requires the use of very little oil and prevents the oil spreading along the trumpet and damaging the silk or other material passing through the trumpet.

Rollers 21 and 22 (Fig. 1) are the delivery or nip rollers of a carding or combing machine, one of which may be connected by a belt 23 to suitable driving mechanism. The

5   nip rollers 21 and 22 deliver the combed or
10   carded material 24 in the form of a ribbon-
15   like sliver in which the fibers are all sub-
20   substantially parallel. The material delivered
25   by the rollers 21 and 22 is drawn into the
30   enlarged end 25 of the trumpet 10 and a bore
35   or passage 26 extending axially of the
40   trumpet and then through a bore or passage
45   27 running at an angle to the axis of the
50   trumpet to an inclined shoulder 28 on the
55   periphery of the trumpet. The material then
60   passes into a bore or passage 29, extending at
65   an angle to the axis of the trumpet from an
70   inclined shoulder 30 on the periphery of the
75   trumpet, and then into a short bore 31 ex-
80   tending axially of the trumpet to the exit or
85   delivery end of the trumpet. After leaving
90   the trumpet the material enters the nip of
95   rollers 34 and 35.

20   Secured to the trumpet 10 is a pulley 36
25   constructed to accommodate any suitable
30   belt or tape (not shown) connecting the
35   trumpet to the driving mechanism.

30   The rollers 34 and 35 are respectively the
35   usual driven roller and co-operating weight
40   roller, although the rollers may be geared
45   together if desired. The roller 34 is driven
50   by any suitable connection to the driving
55   mechanism of the machine to which the mech-
60   anism is applied, and preferably at a periph-
65   eral speed somewhat greater than the speed
70   of the rollers 21 and 22. This difference in
75   speed is sufficient to produce a slight relative
80   or drawing movement of the fibers in the ma-
85   terial in addition to pulling the material
90   through the trumpet, thereby insuring a uni-
95   form movement of the material.

40   In the operation of the device, the rota-
45   tions of the trumpet 10 will cause the eccen-
50   tric portion 38 (Fig. 2) to give a twist in one
55   direction to the material at the right of that
60   portion and a twist in the opposite direction
65   to the material at the left of such portion.
70   This has the effect of compacting the material
75   in the roving and causing greater mutual
80   adhesion of the fibers than would be the case
85   if the material was drawn straight through a
90   tubular interior in the trumpet. However,
95   the speed of the rollers 34 and 35 with refer-
100   ence to the rotations of the trumpet is suf-
105   ficient to cause the twist at the left of the
110   eccentric portion 38 to offset or release the
115   twist at the right before the rollers can re-
120   tain the twist so that the fibers are again in
125   parallelism when the roving enters the nip
130   of the rollers 34 and 35.

60   When starting the machine, a flexible wire
65   having a hook or eye on one end is inserted
70   through the trumpet and the sliver pulled
75   through and engaged with the rollers 34 and
80   35.

65   From the foregoing it is apparent that
70   while the embodiment shown and described
75   is admirably adapted to fulfill the purposes
80   stated, the invention is capable of various em-
85   bodiments, all of which come within the scope
90   of the following claim.

I claim:

70   In combination with a sliver delivering
75   mechanism, a rotary trumpet having a por-
80   tion of its periphery reduced to form shoul-
85   ders oppositely inclined with respect to the
90   axis of the trumpet and an inclined passage
95   leading from each of the shoulders to a bore
100   extending axially of the trumpet to the end
105   thereof, means for rotating the trumpet, and
110   means comprising a pair of driven rollers
115   for drawing the material through said bores
120   and passages and over the reduced portion
125   intermediate the outer ends of said shoul-
130   ders while the trumpet is rotating and at a
135   speed which prevents retaining the twist in
140   the material.

In testimony whereof I hereto affix my signature.

EDWIN O. ROE.
